UNITED STATES PATENT OFFICE.

JOHN C. BROOKS, OF PATERSON, NEW JERSEY, ASSIGNOR TO DRAPER COMPANY, OF HOPEDALE, MASSACHUSETTS, A CORPORATION OF MAINE.

WARP STOP-MOTION.

1,122,850.

Specification of Letters Patent.

Patented Dec. 29, 1914.

Application filed June 6, 1911. Serial No. 631,543.

To all whom it may concern:

Be it known that I, JOHN C. BROOKS, a citizen of the United States, residing at Paterson, in the county of Passaic and State 5 of New Jersey, have invented an Improvement in Warp Stop-Motions, of which the following description, in connection with the accompanying drawings, is a specification, like letters on the drawings representing 10 like parts.

The invention hereinafter described relates to warp stop motions for looms, and more particularly to that type wherein a series of drop devices or detectors are supported by the warp threads, which, upon breakage or undue slackness of one or more 15 of said threads, permit such drop devices or detectors to move into position for co-action with suitable means for stopping the loom. 20 This general type of warp stop motion usually occupies a position between the warp beam and the shedding mechanism, where the limited space precludes the use of a large number of drop devices or detectors and associated parts of the ordinary construction. 25 In weaving certain classes of fabrics, therefore, where a large number of fine warp threads per unit of width are employed, the warp stop motion devices of ordinary construction become impracticable. Moreover, 30 where the drop devices or detectors of ordinary construction are multiplied in two or, at most, three rows transversely of the loom and crowded together in an attempt to 35 adapt such stop motion for use in weaving fine fabrics, the drop devices fail to work properly and much lint or fluff is produced.

With the above facts in view the aims and purposes of the present invention are to provide 40 a warp stop motion of high capacity which shall overcome the difficulties heretofore experienced and be equally applicable for use in weaving the finer fabrics having a large number of warp threads per unit of 45 width or the coarser fabrics having a less number of such threads, and wherein the parts shall be so related and contrived that the drop devices or detectors may be properly guided and supported, and all fluff, lint, 50 or dirt be readily eliminated; all of which

will hereinafter more fully appear in connection with the accompanying drawings of one form of means for carrying the invention into practical effect, it being understood that in its true scope the invention is defined by the claim. 55

In the drawings:—Figure 1 is a side elevation, of a portion of a loom showing the warp stop motion of the present invention associated therewith, some of the parts being shown in section; Fig. 2 is an enlarged detail of one end of the stop motion devices; Fig. 3 is a section taken on the line 3—3 of Fig. 2; and Fig. 4 is a top or plan view of the parts shown by Fig. 2, with portions 60 broken away. 65

The loom frame 1 may be of any usual or desired character suitable for the support of the loom parts. Rising from the loom sides are the stands 2 between the shedding devices or heddles 3 and the whip roll 4 over which the warp threads 5 pass from the warp beam, said parts, as well also as the lay 6, its actuating means and the shipper 7 connected to the loom starting and stopping 70 devices, may be and are shown as of usual construction and operation. 75

Secured on the stands 2 at opposite sides of the loom frame, as by means of the bolts 9, are the end supports 8, constituting one 80 form of end framing for the parts of the warp stop motion. Extending transversely of the loom and supported at the upper portions of the end supports 8, are the warp rods 10, over which the warp threads 5 pass 85 and by which they are sustained. In the present form of the invention each of the warp threads between the warp rods 10, Fig. 3, sustains a drop device or detector 11 and in order that these may be more conveniently and compactly assembled, they are preferably formed of wire shaped generally as indicated by Fig. 3, and having a head portion to engage a warp thread and a tail or extended portion for a purpose to herein- 90 after appear. 95

Mounted on the end supports and extending transversely of the loom are the detector guides for maintaining the detectors in position and directing them in their movements 100

when permitted to drop by broken or unduly slack warp threads. In the illustrated form of the invention these detector guides comprise an upper, a lower, and an intermediate reticulated structure, the openings of which may be so closely related, that regardless of the number of warp threads in the fabric per unit of width, the required number of drop devices or detectors may be 10 employed, it being only necessary to insert or remove drop devices or detectors to correspond to the special requirements of each individual case without disorganizing the elements of the stop motion device.

15 The upper detector guide comprises a framework 12 having secured thereto a series of crossed wires 13, Fig. 4, forming a wire mesh, each of the openings of which is adapted to receive and guide the tail portion 20 of a drop device or detector 11, as shown by Fig. 3. While this form of detector guide is found suitable and convenient, it is to be understood that its characteristics may be secured by the use of a 25 wire fabric of suitable mesh or other reticulated structure. The upper detector guide is secured to the end supports 8 below the plane of the warp rods 10, and as one means to this end, the end supports may each be 30 provided with one or more lugs 14, Fig. 3, to which the upper detector guide may be removably secured, as by the screw devices 15, Fig. 3, or otherwise. The intermediate detector guide 16 may be similarly formed, 35 and supported by lugs 17 projecting from the end supports, and is preferably disposed a suitable distance below the upper detector guide to be engaged by the lower tail portions of the drop devices or detectors when 40 they are in normal position and supported by the taut and unbroken warp threads.

From the construction thus far described it will be seen that the reticulated nature of the upper and intermediate detector guides 45 and the association therewith of the detectors in the manner stated, that a sufficiently large number of such detectors may be employed to provide for the finest character of fabrics woven; that the detectors may be 50 readily removed and replaced without disorganizing the stop motion elements; that fluff, lint, and dirt may be readily removed from between the two detector guides or from the surface of each; and that such 55 cleaning may be facilitated by removing the upper guide and with it the detectors.

Mounted to slide back and forth transversely of the loom below the detector guide 16 is the feeler 18, Figs. 3 and 4, which may 60 be conveniently formed of a series of cross slats carried by a frame 19 slidably mounted in guides 20 formed in or on the end supports 8. The feeler 18 is connected at one end by a pin 21 to the bifurcated end

of an arm 22 rising from a rock shaft 23 65 mounted in the ends 24, Fig. 2, of one of the end supports 8, the construction being such that upon rocking movement of the shaft 23 the arm 22 and perforce the feeler 18 may be moved back and forth, as will be clearly 70 understood by those skilled in the art.

The rock shaft may be operated by any suitable means, such that upon obstruction to its rocking movement, as by the end of a detector dropping in front of a slat in the 75 feeler, said means will actuate the shipper and cause loom stoppage. As such means and their connections with the shipper are well known in the art, a full illustration thereof is not herein deemed necessary, and 80 for detail illustration and description of one appropriate form of such means, reference may be had to the patent to Stimpson, No. 673,824, May 7, 1901, as in said patent the rock shaft 23 has the fixed and loose arms 85 f^1 , f^2 , and connections h^2 , h^3 , with the co-acting means between these parts and the shipper handle, all of which is fully explained in said patent.

Since the lower portion of the tail of a 90 detector is to afford the means for arresting the feeler 18, it is desirable that when a detector moves into detecting position, its end be properly supported or braced, and to this end the present invention contemplates the 95 lower detector guide 25, which may be formed of reticulated material as hereinbefore explained with reference to the upper detector guide, and supported by the lugs 26 of end supports 8; the construction being 100 such that when a detector is permitted to drop either by undue slackness or breakage of a warp thread, it will be guided by the openings in the upper and intermediate detector guides to cause its end, after passing 105 in front of one of the slats of the feeler, to engage an opening in the lower detector guide, and be braced or sustained by said guide in arresting the feeler.

What is claimed is:—

110 In a warp stop motion for looms, the combination of side supports, a feeler, two detector guides disposed in different horizontal planes, each formed of wire mesh material and supported by the side supports and 115 adapted to guide a multiplicity of warp detectors, the upper guide being removably secured to the supports, a series of warp detectors normally suspended from the warp threads and passed through the openings in both of said guides with their lower ends 120 below the lower of said guides and immediately above and in unobstructed proximity to said feeler, and a third detector guide formed of similar wire mesh material and 125 supported by said side supports immediately below said feeler, whereby the lower end of a dropped detector will pass through the

feeler and openings in said last mentioned guide, and be held and braced therein against pressure of the feeler and cause stoppage of the feeler and means actuated by the stopping of the feeler to stop the loom.

In testimony whereof, I have signed my

name to this specification, in the presence of two subscribing witnesses.

JOHN C. BROOKS.
